UNITED STATES PATENT OFFICE.

NILS E. NORSTROM, OF CHICAGO, ILLINOIS.

PARTY-LINE TELEPHONE EXCHANGE.

Application filed June 24, 1926. Serial No. 118,136.

My invention relates to party line telephone exchanges, and has for its object improvements in devices of that type.

In the accompanying drawings

5 Fig. 1 is a diagram of the main part of the central office;

Fig. 1^a is a diagram of an additional part of the central office, and being in fact an extension on another sheet of what is shown in

10 Fig. 1; and

Fig. 2 is a diagram of one of the local stations on the line and an indication of two other stations.

The switching mechanisms at the local stations are mechanically of a well known type, and do not need special description. The only things about them are the electrical connections and such mechanical details as will be evident from the diagram and the description of the operation.

The apparatus in Fig. 1^a is similar to that in Fig. 2, but omits certain things as unnecessary.

In the central office there are a battery and a generator, the purpose of and connections for which will be evident from the description of the operation. There is also a switching device having two wipers, and a set of contact points for each wiper. The number of contact points in each set is equal to the number of stations that are or may be on the party line. This switching mechanism is controlled by a keyboard having a series of numbered keys to correspond to the number of stations on the line.

There are also certain electrical connections operated by magnets, a switchboard key, a plug and jack, a drop, and other devices, the character of which will become evident from the description to follow.

In the present case, the local stations are connected to the central office by one wire and ground, thus obviating the use of a second wire which is common in party line exchanges. Or the local stations may be connected to the central office by a metallic circuit consisting of two wires with no ground connection. While it is not new to connect a series of local stations to a central office by one wire and ground only, such systems have been limited in a number of ways. The purpose of the present system is to obtain by one

wire and ground connections all of the advantages which have heretofore been obtained only by the use of two wires and a ground connection.

In the present drawings I have illustrated connections for three stations, which are all that are necessary to explain the system. It is to be understood, however, that the number of stations on the line are usually more numerous, the apparatus being commonly made for twenty stations on a line. To illustrate the operation we will assume that the subscriber at station No. 1 calls central and wants to talk with the subscriber at station No. 3.

The subscriber at station No. 1 turns the crank of his generator G, whereupon a current flows as follows:—G—1—2—3—4—5—6—7—8—9—10—11—drop D—13—14—ground at 15 to ground at 16 at station No. 1—18—19—20—21—G.

When ringing from the generator G, there is a branch from 4 thru the stepping up magnet H to ground at 16, and this causes an operation of the stepping up magnet. However, this circuit goes thru 18—19—20, and the beginning of the movement of this magnet breaks its own circuit at 19. The consequence is that while the impulses from the generator G operate the drop D, they are broken up at 19 so that the stepping magnet is not operated effectively.

The impulses over the circuit just given operate the drop D at the central office, but affect nothing else. The operator inserts the plug F in the adjacent jack, and presses the switchboard key K to the right to connect her telephone set. Beginning at the receiver at station No. 1, the talking circuit is:—R—1—2—3—4—5—6—7—22—23—24—25—26—27—telephone set—28—29—30—31—32—14—ground at 15 to ground at 16—17—18—19—20—21—33—hook—34—R.

Upon being informed that station No. 1 wants to talk to station No. 3, the operator presses keys No. 1 and No. 3 on her keyboard. These keys are made of insulating material, and each one rests on two contact springs which are spread when the corresponding key is depressed. Adjacent to each key is a catch, a part of one of which is shown at 35 adjacent to key No. 2. When a key is depressed, its

catch engages and holds it until the catch is later released.

In pressing down a key on the keyboard, the inner electrical connection is broken, and other electrical connections are made at the outer sides of the springs which are spread by such depression. In such depression the key is moved downward so that the ledge 36 on the key passes a short distance below the adjacent catch 35. When the operator removes her hand the key rises to engagement with the catch. The outer contact springs are so arranged that the one to the left (above as shown in Fig. 1) is a little nearer to its adjacent contact spring than is the one to the right. When a key is depressed, contact is made to both of the outer springs, but each catch 35 is so related to these springs that when the operator removes her hand from a depressed key and it rises to its catch, such rise breaks the more distant contact and leaves the other in engagement.

When the operator depresses a key, and before she removes her hand to permit the depressed key to rise to its catch, a current flows from the battery X thru line 37 and branches 38 and 39 to spring 40 of the highest numbered key on the board. If that key is depressed, as in the present assumption, then the circuit for this current continues—41—42—43—master magnet M—44—45—46—47—A—48—49—50—51—X.

If, however, the highest numbered key on the keyboard is not depressed, then the circuit would be from 40 of the highest numbered key—53—54—40 of the next key, and so on until it came to a depressed key, after which it would go thru the corresponding spring 41 of that key to the line 42, and then as before described.

The circuit just described permits the flow of a current to operate magnets M and A, but this circuit is immediately broken by the depressed key rising to engagement with its catch 35. However, the operation of the magnet M shifts its adjacent contact springs to hold its own circuit from 38—55—56—43 and so on as before. The operation of the magnet A moves the holding pawl 57 into engagement with the ratchet wheel B, and holds this until the circuit thru M and A is broken as will be described hereinafter.

The ratchet wheel B is operated by a magnet C with its armature 118 and attached pawl. On the wheel B is a wiper 117 which is in electrical connection with the wheel. The wheel, wiper 117 and armature 118 are all in connection with the base of this switching device so that an electrical connection to one of them is a connection to the others. Also on the wheel B is an insulated wiper 148 which is connected with a wire 149 as shown. The wheel B and associated parts may be called a master switch.

The teeth of the wheel B are comparatively

fine, and the wiper 117 is so located that it does not reach the first contact point of its series until the wheel has advanced five steps beyond its normal position, which is that shown in the drawing. The insulated wiper 148 is so located that it does not reach its first contact point until one step after wiper 117 reaches its first contact point. Also, the contact points are so spaced that it requires two steps of the wheel to advance a wiper from one contact point to the next one in the series. Under the arrangement described, when wiper 117 reaches its first contact point, wiper 148 is one step away from its first contact point. At the next step, the wiper 148 comes to its first contact point and the wiper 117 comes to the space between the first and second contacts. At the next step, wiper 117 comes to its second contact point and wiper 148 comes to the space between its first and second contact points.

When keys Nos. 1 and 3 are depressed, the first and third contact points for wiper 117 are made alive by connecting them to the battery thru the line 37 and 38, and the springs 39 to the left (above in Fig. 1) of the depressed keys. All other contacts of this series are dead.

If key No. 1 is depressed and no other key, then the battery X is connected thru 37—38—39—40 of key No. 3—53—54—40 of key No. 2—and by a similar loop with 40 of key No. 1. As the springs 40 of all keys except the highest numbered key are connected directly to their respective contacts in the path of wiper 148, and as the highest numbered contact is connected directly with the line 37, it will be evident that pressing key No. 1 makes alive all contacts in the path of wiper 148.

After the operator has depressed keys Nos. 1 and 3 of the keyboard, she moves key K to the left to shift the adjacent contact springs. A current then flows as follows:—X—37—57—58—59—60—61—62—63—S¹—64—65—66—67—24—23—22—7—6—5— of all stations on the line — operating magnets H to ground at 16—ground 15 at jack—14—32—31—30—68—69—70—71—72—73—74—75—76—77—78—52—X. A branch of this current goes thru 5^a and magnets H¹ in Fig. 1^a.

This current is in the release direction thru the stepping-up magnets of the local stations, and thru the corresponding magnet in Fig. 1^a. Its purpose is to insure that all switching mechanisms at these places are in their normal positions.

The current just described also went thru the coil S¹ to operate its armature and shift the adjacent contact springs. When this occurs a current flows:—X—79—80—81—82—S²—83—84—85—86—X. The coil S² is on the same core with S¹, and the current thru S² serves to hold the adjacent springs in their shifted position when the circuit is broken thru S¹ in subsequent operations.

When S^1 and S^2 shift their adjacent contact springs and hold them in that shifted position, a circuit is closed for magnet P as follows:— $X-37-87-P-88-89-90-91-92-93-86-X$. Also:— $X-79-94-95-96-C-97-90-91-92-93-86-X$.

5 This operates the magnet C to advance the ratchet wheel B one step, and operates magnet P to break its own circuit at 88, and the 10 circuit for the magnet C at 94. But this last circuit is quickly remade by spring 95 coming into contact with spring 98. As a consequence of this, magnet C operates once when magnet P operates, and again when the 15 circuit for P is broken. In other words, magnet C operates twice for each operation of magnet P .

At the time magnet P operates to shift the 20 movable springs to the right it brings spring 73 into connection with contact 58, whereupon a current flows:— $X-37-57-58-73-72-71-70-69-68-30-31-32-14$ — ground at 15 to ground at 16 of all local stations on the line—stepping magnets $H-5-6-7-22-23-24-67-66-65-64-S^1-63-62-61-60-59-99-100-52-X$. There is a branch of this which goes thru the corresponding stepping magnet of Fig. 1^a.

The current flowing thru the circuit just 30 described is an impulse in the stepping up direction, and acts to advance the switching mechanisms of all stations one step.

At each of the local stations there is a pin 35 101 in the path of the driving pawl so that the ratchet wheels will be advanced only one step for each impulse of this kind. For the corresponding ratchet wheel 103 of Fig. 1^a there is no corresponding stop, with the result that each stepping impulse causes this wheel to 40 move a distance of two or three teeth when the wheels 102 move only one step each. The object of this is simply to cause the wheel 103 to advance further than the wheels 102 so that when they are all released at the same 45 time the wheel 103 will not reach its normal position until after the other wheels have done so. It is to be understood that all of these wheels have holding pawls which retain the switching devices in their advanced position 50 until released. These holding pawls and the releasing mechanisms are not shown as they are well known in the art and form no part of the present invention.

When P attracts its armature 104 and 55 breaks its own circuit as previously described, a spring 105 retracts the armature to remake the circuit for P . As it is desired that the magnet C should operate twice while the magnet P operates once, the armature 104 is 60 made heavy so that it will not move rapidly.

On the pivot 106 of the armature 104 is loosely pivoted a weighted arm 107 which is free to vibrate between pins 108 and 109 secured on the armature 104. When the armature is attracted, the pin 108 drives the arm

107 forward at the same speed that the armature moves. When the armature is arrested by breaking the circuit thru the magnet P , the arm 107 continues to move forward until it engages pin 109. At this time the spring 70 105 is beginning to retract armature 104, and the result of the collision between arm 107 and pin 109 is to retard the retraction of the armature 104. As a consequence, the momentum of the arm 107 in passing from pin 108 75 to pin 109 is to check the rate of vibration of the armature, and this is equivalent to adding considerable weight to that armature. In the same way, the passage of the arm 107 from pin 109 to pin 108 on the return stroke checks 80 the rate of vibration at the other end of the stroke.

The armature 104 is retracted by spring 105, and in this movement the arm moves at 85 the speed that the armature moves. The back stop for the armature is an electrical contact for completing a circuit for the magnet P , and is placed on a spring 89 so that there will be a material period of time during which this electrical connection is held. 90 There is a tendency for an armature in this condition to rebound from its back stop and set up vibrations which interfere with the proper operation of a device of this kind. The momentum of the arm 107 in passing 95 from pin 109 to contact with pin 108 checks this vibration and retains the connection with spring 89 until that connection is broken in the regular order by a new operation of the magnet P .

On the ratchet wheel B is a cam 110 against which rests the spring 76. When the wheel is advanced, this cam operates to move the spring 76 out of engagement with the contact point 77. This occurs at the first or second step of the wheel. When the armature 104 falls back again it closes a circuit in the release direction thru the stepping magnets of the stations as before. But this occurs after the wheel B has advanced two steps, and consequently after the connection has been broken at 77. The result is that this release impulse goes from branch 75 thru the resistance 111 to branch 78. This resistance lets thru current enough to kill the residual magnetism in the stepping magnets, but not enough current to release the switches.

At about the third time the magnet P attracts its armature, which would correspond to the fifth forward step of the ratchet wheel B , the wiper 117 comes into engagement with the first contact point 116 in its path. As the armature 118 of magnet C falls back, a circuit is completed as follows:— $X-37-38-112$ —of key No. 1—113—114—115—116—117—base—118—119—120— $E-121-122-52-X$.

Before proceeding with a description of the effect of an impulse over this circuit and thru the magnet E , we will refer to the appa- 130

- ratus at the local stations. On each wheel 102 is a cam 123 which corresponds to cam 110 and serves to move the spring 2 from its upper to its lower contact at about the second step of wheel 102. Also on each wheel 102 is a cam 124 arranged to engage a spring 136 and push it outward into electrical contact with spring 137. At station No. 1 this would occur at the third forward step of the wheel 102, and would be co-incident with the wiper 117 engaging the first contact 116. At station No. 2 the cam 124 at that station would engage its adjacent spring at the fourth forward step of the corresponding wheel 102, and co-incident with the wiper 117 engaging the second contact of its series. At station No. 3, the corresponding operations would occur at the fifth forward step, and so on for the other stations on the line.
- 20 Returning now to the impulse thru the magnet E, the attraction of its armature shifts the connection from contact 61 to contact 132, whereupon a current flows as follows:—alternating generator Q—126—127—128—129—131—132—62—63—S¹—64—65—66—67—24—23—22—7—6—5 of station No. 1—4—133—cut-in magnet 134—135—136—137—ground at 138 to ground at 139—140—Q.
- 30 This operates the cut-in magnet 134 so as to attract its polarized armature 141 and shift the adjacent contact springs. Adjacent to the armature 141 is a hooked lever 142, the other end of which is engaged by pin 143 on wheel 102. When this wheel is at its normal position, this pin or projection 143 engages the lever to hold its hook free from the armature 141, but when the wheel advances under the action of its stepping up magnet, the hook 142 is in condition to engage and hold armature 141 in attracted position as soon as its magnet 134 acts. The purpose here is to hold the adjacent springs in their shifted position.
- 40 The generator Q operates at about twenty to forty cycles per second. From the circuit last described there is a branch which goes thru the magnet I, and its armature 127 is in the circuit for the cut-in magnet 134. The result of this arrangement is that the impulses going from generator Q are broken up into small fractions. The magnet 134 will operate to move its armature under these impulses because said armature has no direct retracting spring. There is a small space 144 under the hook 145 which is carried by the armature 141. As a consequence, when the hook 145 strikes the spring 164 to shift the electrical connections, the momentum of the moving parts is sufficient to make the shift and have the armature caught by hook 142.
- 50 In the circuit from the generator Q, there is a branch from line 5 thru the stepping up magnets, but the armatures of these magnets are held in central position by compara-

tively strong springs 18 and 20, and the current from Q is not powerful enough to operate these magnets under these conditions.

When the magnet C again operates it moves wiper 148 to its first contact point, and the wiper 117 to the vacant space between its first and second contact points. If key No. 1 was the only one depressed, then a circuit will be formed as follows:—X—37—38—39—40 of the highest numbered key on the board which in this case is key No. 3—53—54—40 of key No. 2—similar loop to 40 of key No. 1—146—147—148—149—magnet N—122—52—X. If key No. 2 was depressed, then the circuit would be broken at 40 of key No. 2 and there would be no impulse thru magnet N. A circuit would, however, be established when wiper 148 reached the second contact by wire 150 from 40 of key No. 2. In the present case we have key No. 3 depressed and the circuit broken at 40 of key No. 3 for all contacts of lower numbers in the path of wiper 148. The last contact of this series is connected directly to battery X by branch 151 from line 37, and magnet N will be operated when the wiper 148 reaches this contact.

When wiper 117 comes to a contact point, it does nothing immediately or directly, but if the correspondingly numbered key is depressed, then a circuit is completed for magnet E when the armature 118 falls back. The operation of E throws impulses onto the line, and these impulses go thru the cut-in coil of the correspondingly numbered station. On the assumption that keys Nos. 1 and 3 are depressed, then when wiper 117 comes to its first contact point the battery X will be connected to wiper 117 thru spring 114 of key No. 1, and when the armature 118 falls back this connection will be extended thru the magnet E to the other pole of the battery. This will put impulses from Q thru cut-in coil 134 at station No. 1 because at that station cam 124 has the contact springs 136—137 closed. When wiper 117 comes to its second contact point, nothing of this kind will occur because key No. 2 is not depressed and its spring corresponding to spring 114 of key No. 1 will be open. But when wiper 117 comes to its third contact point, the previous active conditions will be repeated because key No. 3 is depressed and because the springs 136—137 are closed at this time at the third station.

In the previous description it was pointed out that when wiper 148 comes to the contact point of its series which corresponds to the highest numbered key depressed, there is a circuit completed thru the magnet N. The resultant actuation of this magnet breaks the circuit for the magnets M and A at the point 46.

Breaking the circuit thru the magnet M permits the adjacent contact springs to return to normal position, and as the other

magnets are controlled thru these springs in their shifted position, the parts controlled by those other magnets also return to normal position as is common in exchanges of this character. And breaking the circuit thru magnet A releases the holding pawl from wheel B and permits that wheel to return to normal position. By suitable connections, the return of the various parts to normal position releases catches 35 so that the depressed keys on the keyboard may rise to their normal positions. These connections are not shown because there is nothing new or novel about them, and because they form no part of the present invention.

During these operations the operator is holding her key K to the left, and as soon as the parts controlled by magnet M have returned to normal position, a current flows:—
20 Q—126—127—128—152—66—67—24—23—
22—7—6—5 of the selected stations —4—
133—153—154—155— ringer 156— hook
158—33—21—20—19—18—17— ground at
16 to ground at 139—140—Q.

25 This serves to operate the ringers at stations Nos. 1 and 3 to call the subscribers thereat, and this ringing operation is arrested by the operator releasing her key K. When the subscribers have removed their receivers, the talking circuit is:— R at station No. 1—1—2—159—160—161—162—163—
30 164—153—133—4—5—6 to station No. 3—
5—4—133—153—164—163—162—161—
160—159—2—1—R—34—158—33—21—20—
35 19—18—17— ground at 16 to station No. 1—
17—18—19—20—21—33—158—34—R.

When the subscribers are thru talking they turn their generator cranks, or at least one of them does, and a current flows as follows:—
40 G—1—2—159—160—161—162—163—164—
153—133—4—5—6—7—22—23—24—25—
45 clearing out drop 165—29—30—31—32—
14— ground at 15 and back to ground at 16 at local station —17—18—19—20—21—G. The operator thereupon removes the plug to disconnect the line.

In describing the first stepping up impulse thru the station devices it was stated that a branch went thru 5^a and the stepping up magnets of Fig. 1^a. Adjacent to these magnets is a contact spring 167 which is pushed into engagement with a contact 166 whenever these magnets are operated in the stepping direction. At the time the first stepping up impulse flows as described, this electrical connection is made and a current flows:—
50 X—37— to Fig. 1^a —166—167—168—169—
170—171—172— magnet 173—174—175—
55 176—177—85—86—X.

60 This operates to shift the contact springs adjacent to the magnet 173, and this shifted position is held by the armature 178 being caught and held by the catch 179 which was released by the first forward step of wheel

103. At the time the operator removes the 65 plug as before stated, an impulse flows as follows:— X—37 to Fig. 1^a —178—179—9—8—
7—6—5^a and 5 of all stations on the line —
stepping magnets H and H¹ — ground back 70
181—175—176—177—85—86—X.

This is an impulse in the release direction thru all of the switching mechanisms, and is held until the wheel 103 of Fig. 1^a reaches its 75 normal position and releases catch 179 from armature 178. As previously stated, wheel 103 advances further than do wheels 102, and the result is that this current in the release direction is not broken until after the switching mechanisms at the local stations have had ample time to reach normal position. But when wheel 103 does reach its normal position, all parts are automatically returned to normal position.

Reviewing the operations very briefly, the 80 subscriber calls central in an ordinary manner and tells the operator the station with which he wishes to talk. Upon receiving the desired information, the operator presses the 85 keys on the keyboard which represent the calling and the to-be called stations, and immediately thereafter moves her switchboard key K to the left. The act of depressing the keyboard keys starts a series of automatic electrical operations within the central office 90 which prepares the apparatus therein for sending impulses over the line to select the desired stations and connect them telephonically to the line, and at the same time to lock out all unselected stations. The act of pressing 95 the switchboard key results in starting the prepared apparatus into automatic operation to select and signal the desired stations and then to return itself to its normal position as it existed before the depression of 100 the keyboard keys.

Reviewing some parts again, but not quite so briefly, the operator depresses a key representing the desired station. This operation breaks one electrical connection and makes 110 two others, one of which is temporary and the other of which is held. The connection broken is a series connection between keys and cuts off from the series all keys of a lower number than the one depressed. The temporary connection sends an impulse to operate a master magnet M and to shift a series of electrical connections, and to operate a magnet A to put a holding pawl in contact with a master switch B. The connections 115 shifted produce a holding circuit for magnets M and A. The connection which is held is one leading from the battery to a corresponding contact point on the master switch in the path of wiper 117.

120 After depressing a key or a plurality of keys on the keyboard to get the results just described, the operator shifts the switchboard

key to the left to send a release impulse from the battery thru all of the stations on the line and thru coil S^1 to shift adjacent springs. This last makes a holding circuit thru the coil S^2 which is independent of the impulses thru the stations.

The springs shifted by magnets S^1-S^2 close a circuit for the magnet P , which is the motive part of an impulse sender, and for the magnet C to operate the master switch. This impulse sender is in the form of a slow speed vibrator, and might properly be called a pole changer because the impulses sent are alternately in the opposite direction. The operations of the magnet P close connections for the magnet C at the terminal of each vibration of the parts vibrated so that the magnet C operates at twice the frequency of magnet P .

At each attraction of its armature by the magnet P an impulse in the stepping up direction flows thru all stations on the line, and at each retraction an impulse in the release direction flows thru all stations. But the first forward movement of the master switch inserts resistance in the branch for these release impulses so that they are ineffective to produce actual release.

When the wiper 117 reaches a contact corresponding to a depressed key, battery connections are extended to that wiper, and when armature 118 falls back an impulse goes thru magnet E . The operation of E shifts the party line from the battery to the generator Q so that broken up impulses flow thru the cut-in magnet of the station which corresponds to the key depressed on the keyboard.

The effect just described will be repeated each time the wiper 117 comes to a contact corresponding to a depressed key. Wiper 148 is one step behind wiper 117, and when wiper 148 comes to its contact which represents the highest numbered key depressed, a current flows thru the magnet N to cause a restoration of all of the central office apparatus to its normal position. During these operations the operator is holding her switchboard key K to the left, and when these parts return to normal position ringing impulses flow from generator Q over the line and thru the bells of selected stations.

The pole changer which serves as an impulse sender is one which works automatically when started into operation, and which automatically comes to a stop at a definite position as soon as it has sent the number of impulses previously indicated by the manual operation of the keyboard. This automatic stoppage saves wear and tear of parts which occur in pole changers which operate continuously. The fact that the pole changer always stops in a definite position insures that it will be in proper position to send a release impulse thru the stations when the

operator removes the plug to disconnect the line. This would not occur in the case of a pole changer which was a continually operating device.

When the operator inserts her plug in response to a call from some subscriber on the line, such insertion breaks the circuit for the drop D at the spring 14. When the first stepping up impulse flows, the branch thru the magnet H^1 closes another branch thru the magnet 173 of Fig. 1^a and this magnet breaks the circuit for the drop at another place so that, on removing the plug to disconnect the line the resultant release impulse will not flow thru the low wound drop. This is important because the party line may be twenty miles long or more, and if the drop was in parallel with the stations, not enough current would go thru to release the stations.

At the local stations, from each branch there is a sub-branch 4 which leads to the cut-in coils 134. In this sub-branch is a condenser 200 to prevent the battery impulses for magnets H from also operating the cut-in coils. Each time a stepping impulse flows over the line it gives each condenser 200 a charge, and when the impulse ceases, the condenser is discharged and causes a light impulse to flow thru the associated magnet 134. As the armature 141 of this magnet is polarized and has no retracting spring, the impulse of discharge is sufficient to move the armature on its pivot. The polarization of this armature is so related to the direction of impulse due to discharge that the end which carries the hook 145 is moved away from the pole of the magnet.

As previously described, the alternating generator Q runs at comparatively slow speed, and the magnet I operates at high speed. The result of this arrangement is that the impulses which go from generator Q over the line are really each a series of very short impulses in one direction followed by a series of equally short impulses in the opposite direction. When the magnet E is operated to shift the line from the battery to the generator Q , the first broken up impulses from the generator find the armature 141 prepared by being tilted on its pivot away from the position to which it is to be moved by those impulses. If the first broken up impulses are of the same direction as the discharge from the condenser, then they are without effect. But when the impulses are in the opposite direction, they operate to move the armature thru a considerable distance before the resistance of contact spring 164 is encountered, and during that non-resisted movement the armature acquires momentum which enables it to overcome the resistance of the spring 125 and permit the armature to be caught and held by the hook 142.

The circuits at the local stations are so ar-

ranged that at the non-called stations the receiver R and the generator G are shunted so that a subscriber not called cannot listen in and cannot send signaling impulses which will disturb a conversation going on. The shunt for the receiver is:— R—1—2—159—160—161—162—163—164—201—202—21—33—158—34—R. As the receiver R and generator G are in parallel between 1 and 21, the shunt for the generator is the same.

At each local station is a spring supported at 204 and having a weight 214 on its free end. Nearby is a frame 205 which carries a spring-supported pin 206 having a button 207 which may be reached by the subscriber. These parts are so arranged that if the button 207 is depressed quickly, the pin 206 will strike the spring 203 and the momentum given to the weight by such quick stroke will carry spring 203 far enough down to strike spring 161 and break its contact with spring 162. But the parts are also so arranged that holding the button 207 depressed does not hold spring 161 from spring 162 because the pin 206 is too short to maintain this condition. The connection between 161 and 162 is in the shunt previously described. Depressing the button 207 slowly will not affect this connection, but depressing it quickly gives the weight a momentum which will result in a very brief opening of the connection between 161 and 162.

If a subscriber who is locked out turns his generator G, and while turning it gives his button a series of taps, the generator shunt will be broken at intervals, and at each break current will flow as follows:— G—1—2—159—160—161—203—133—4—5—6—7—22—23—24—25— clearing out drop 165—29—30—31—32—14—15—ground to 16 at local station—17—18—19—20—21—G.

This would operate the drop which is ordinarily used to indicate that a conversation is finished. In ringing off, the operation of the drop 165 is accompanied by a buzzing sound plainly audible to the operator, but the operation of the drop by an emergency signal of this kind would be by single ticks separated by intervals. The distinction between the two is readily observable by the operator who would know that a signal of this kind was an emergency call from some locked out subscriber. Upon receiving such signal she would proceed in the ordinary manner to answer the emergency call.

The party line consists of two line limbs which connect a central office and a series of local stations together. One limb is a wire, and the other limb is either a wire or ground connection as circumstances may dictate. These two line limbs constitute a path over which electrical impulses flow in different forms and at different times to make a complete and effective party line system. These electrical impulses are the call signal from a

local station to the central office, talking between subscriber and operator, initial release impulse to insure that all local station devices are at their normal positions, stepping impulses going thru all stations, cut-in impulses thru selected stations, call signals to subscribers, talking between subscribers, emergency signals, and ringing off. The apparatus and operations described are for producing these results in an efficient manner when that single path is the only means of intercommunication.

What I claim is:

1. A slow speed pole changer, a master switch having wipers insulated from each other and a series of contact points in the path of each wiper, and means including a battery and connections so arranged that the master switch will make one forward step at each alternation of the pole changer. 85

2. A slow speed pole changer, a master switch having wipers insulated from each other, a series of contact points in the path of each wiper, said wipers and contact points being so arranged that the wipers will come to their respective contact points at alternate forward steps of the master switch, and means including a battery and connections so arranged that the master switch will make one forward step at each alternation of the pole 95 changer.

3. In a telephone exchange having a series of local stations on a party line, a master switch having two sets of contact points each set of which has as many contact points in it as there are stations on the party line, a wiper on the switch for each set of contact points, said wipers being so arranged that they come to their contact points at alternate forward steps of the switch, and an impulse sender 100 controlling the operations of the switch and itself operating at one-half of the frequency of the switch. 105

4. In a telephone exchange having a series of stations on a party line, a master switch having two sets of contact points each set corresponding to the stations on the line and also having a wiper for each set of contact points, a keyboard having keys corresponding to the stations, an impulse sender arranged to send impulses over the line to the stations and also to operate the master switch, means by which depressed keys on the keyboard control part of the operations of the master switch, and means by which the master switch controls part of the impulses sent by the impulse sender. 115

5. In a telephone exchange having a series of stations on a party line, a master switch having two sets of contact points corresponding to the stations on the line and a wiper for each set of contact points, said wipers being insulated from each other so arranged that they come to their contact points at alternate forward steps of the switch, means for mov- 125 130

ing the switch step by step, means for sending electrical impulses over the line to select desired stations and connect them telephonically to the line, and means for controlling such impulses thru the wipers of said switch.

6. A party line having local stations thereon, two magnets at each station by the operation of which desired stations are connected telephonically to the line and other stations are excluded from such connection, two sources of electricity located at the central office, manually operated means for connecting the line to the central office, automatically operating means by which impulses flow over the line to operate simultaneously corresponding magnets at all of the stations, and additional automatically operating means by which impulses from the second source will flow over the same path between stations to operate the second magnet at some previously determined station.

7. A party line having a series of local stations connected to a central office by a single electrical path, two magnets at each station, one of the magnets at each station being responsive in opposite ways to impulses of a given character but in opposite directions and the other magnet being responsive to impulses of a different character, two sources of electricity at the central office each of which is adapted to furnish impulses suitable for the operation of one kind of said magnets, and automatically operating means for causing impulses to flow from both sources over the same path to connect desired stations telephonically to the path over which the impulses flow.

8. A local station connected to a party line, two magnets in the station and connected in parallel between the limbs of the line, means for sending direct and alternating impulses at different times over the line, and a condenser in the branch for one of said magnets, said condenser serving to prevent direct impulses from operating said magnet and by its discharge between impulses serving to prepare said magnet for subsequent operation by alternating impulses.

9. The combination with a central office, a party line having local stations thereon, and apparatus at the local stations operated by impulses flowing over the party line, of a battery, an impulse sender automatically operated from said battery, and means by which upon the impulse sender being started into operation it will send a predetermined number of impulses over the party line and will automatically come to rest at the position from which it was started.

10. A pole changer, a battery from which the pole changer is automatically operated and from which it sends impulses alternately in opposite directions over a line, and means including manually operated keys and connections controlled thereby by which upon

the pole changer being started into operation it will send any predetermined number of impulses over the line and then automatically come to rest at the position from which it started.

11. A party line having a central office and any desired number of local stations thereon, apparatus operated by selecting and connecting magnets at each station, both of which magnets are operated over the same path between stations and office, a source of electrical impulses for the selecting magnets and another source of impulses for the connecting magnets, means for automatically shifting the line from one source to the other and back again, and means for returning the operated apparatus from any degree of advance by an impulse sent over the same path used for selecting and connecting impulses.

12. A party line having a central office and a series of local stations thereon, selecting and connecting magnets at each station, both of which magnets are operated over the same path between stations and office, automatically operating means for sending impulses from the office for operating all of the selecting magnets and predetermined ones of the connecting magnets, and automatically operating means for arresting the impulse sending operations as soon as the predetermined connecting magnets have been operated.

13. A party line having a series of local stations thereon, a central office provided with a source of electricity to operate and release devices at the local stations by impulses sent over the party line, a signaling device by which a subscriber at a local station calls the operator at the central office, a plug and jack for connecting the line to the office apparatus and for breaking the circuit for the signaling device by such insertion, means for sending operating impulses over the line after the plug is inserted and a release impulse when the plug is removed, and means operated by the first operating impulse to break the circuit of the signaling device at another place so the release impulse will not flow thru the signaling device.

14. A central office and a series of local stations connected to the office by a party line, means for sending impulses over the line to connect selected stations telephonically to the line and to exclude non-selected ones by shunting the receivers and signaling generators thereat, and an emergency button located at each station by the pressing of which the subscriber thereat may break the shunt for his generator for an automatically limited period to permit a signaling impulse to flow from the generator to the office.

15. A central office and a series of local stations connected to the office by a party line, means for connecting selected stations telephonically to the line and for excluding other stations from all electrical connection with

the line, and an emergency device at each local station by the operation of which a subscriber at an excluded station may obtain electrical connection with the line for an automatically limited period to signal the central office.

16. In a party line system in which selected stations are connected telephonically to the line and unselected stations are excluded by 10 having their receivers and signaling gen-

erators shunted within their stations, an emergency button at each station, and a weight movable from normal position by a sudden depression of said button, the momentum of the weight serving to make a very brief break in the shunt which will let thru a very brief signal from the generator, but will not otherwise affect said shunt.

NILS E. NORSTROM.
